UNITED STATES PATENT OFFICE.

PHILIP KAUFMAN, OF BALTIMORE, MARYLAND, ASSIGNOR TO LIZZIE KAUFMAN, OF SAME PLACE.

STORM-SUIT.

SPECIFICATION forming part of Letters Patent No. 623,086, dated April 11, 1899.

Application filed March 22, 1898. Serial No. 674,735. (No model.)

To all whom it may concern:

Be it known that I, PHILIP KAUFMAN, a citizen of the United States, residing at Baltimore, in the State of Maryland, have invented 5 certain new and useful Improvements in Storm-Suits; and I do hereby declare the following to be a full, clear, and exact description of the invention, such as will enable others skilled in the art to which it appertains to make 10 and use the same.

My invention relates to storm or other suits, and while especially designed for riders of bicycles and horses it is equally well adapted for those who are engaged in all kinds of outdoor athletic sports; and the improvements consist, essentially, in combining, with a novelly-constructed hooded cloak or cape, a pair 15 of leggings which are attached to the lower portion of the cloak and are adapted when not 20 in use to be concealed on the inner side of the cloak.

The invention further consists in certain other novel features of construction and the combination and arrangement of parts, as 25 will be hereinafter described, and set forth in the claims.

The primary object of the invention is to produce a storm-suit which will afford complete protection for all parts of the person 30 from rain and at the same time permit the wearer, if a rider, to have full control of his horse or bicycle; and a further object of the invention is to provide means whereby the cloak or cape and leggings, if desired, may be 35 arranged and worn after the rain has ceased with but little (if any) discomfort or inconvenience to the rider.

In the accompanying drawings, Figure 1 is 40 a perspective view of my improved hooded cloak open and showing the manner in which the leggings are attached to and supported by the cloak when not in use; Fig. 2, a plan view of one of the leggings detached from the cloak; Fig. 3, a perspective view of one of the 45 leggings, showing the sides properly laced; Fig. 4, a side view, slightly perspective, showing how the hooded cloak may be worn drawn or "bunched" into folds at the back when not in actual use; Fig. 5, a perspective view 50 of a person provided with the suit complete; Fig. 6, a front view of the hooded cloak open

and showing the leggings detached; and Fig. 7 a diagram of a modification of my suit, showing it cut from two pieces of material.

Referring to the several views, the numeral 55 1 indicates the cloak or cape, which is provided with a proper collar 2 and a hood 3, having a suitable vizor 4. The cloak is preferably composed of three pieces—a middle or back breadth *a* and two side breadths *b*—although it may be made of any suitable number of pieces necessary to produce the proper shape, and it may be made of any of the well-known "waterproof" fabrics.

The hood is of peculiar construction. It is 65 made of two pieces *c c*, slightly rounded and projecting at the top, so that when stitched together and provided with the vizor 4 the upper portion will have the appearance of a cap. The hood is joined to the cloak, preferably by 70 stitching, and is provided on opposite sides, in a position about where the ear of a person would be when the hood is in use, with a series of perforations 5 for the purpose of permitting the wearer, especially if a bicycle-rider, to have his sense of hearing unimpaired 75 and also to afford a free circulation of air. In case the rain or wind should be such as to cause discomfort to the rider, flaps 6 are so arranged that the perforations may be readily 80 covered to shut out the rain or wind on either or both sides, as may be desired.

Fastened near each side edge of the cloak 85 at 2 is a drawing-string 7, the free end of each string passing through a perforation 8 at the center of the cloak and collar-band, so as to be within easy reach of the person wearing the suit when it is desired to draw or bunch the cloak into folds at the back, as shown in Fig. 4. If desired, a second drawing-string 90 9 may be employed to confine the lower portion of the folds to prevent spreading by rapid riding or the wind. On the inner side the cloak is provided with suitable arm-straps 10 10, which serve when the arms are passed 95 through them to prevent the sides of the cloak from flying back if partially unbuttoned.

The inner bottom edge of the cloak is preferably provided at each side thereof with three buttons or clasps 11 11 11, to which are 100 detachably secured straps 12 12 12, which are adapted to support the leggings 13 13 when in

use and not made in one piece with the cloak. Each legging is preferably made in two pieces *e f*, cut and stitched together at the rear to approximately conform to the shape of the leg and to lace at the side, as shown in Figs. 2 and 3. The leggings, as heretofore stated, are preferably supported from the cloak by the straps 12, which are detachably fastened to buttons or clasps 14 14 14, secured to the upper edge 10 of the leggings. The leggings are further supported when in use by adjustable supporters 15 15, which are buttoned onto buttons 16 16, one on each side edge of the legging, and have their free ends formed with a loop 17, 15 through which the belt of the wearer passes, as shown at 18, Fig. 5. Should the person wearing the suit be without a belt, one side of the loop is provided with a buttonhole, so that the supporter may be buttoned to the 20 waistband of the trousers, or the suspender-ends may be passed through the loop. When not in use, the supporters 15 are buttoned on the buttons 14 at the upper edge of the leggings, as shown in Fig. 2, and the leggings, 25 which are provided with suitable eyes 19, are brought or turned up and fastened to hooks 20, secured to the upper edge of the cloak, as shown in Fig. 6, thus neatly disposing of the leggings in a convenient manner, allowing 30 the cloak to be worn in folds at the back of the person.

The numeral 21 indicates two straps which are secured a slight distance apart to the upper edge of the cloak and approximately in 35 the center thereof. The free end of one of these straps is provided with a buckle 22, in which the free end of the other strap is secured when the suit is to be worn. Placket-openings 24 24 may be made in the respective sides 40 of the cape to be used for the insertion of the arms when desired.

To adjust the suit to a person, the bottoms of the leggings are detached from the upper edge of the cloak, fitted to the respective legs 45 of the person, and properly laced or buttoned at the sides. The supporters 15 are then unbuttoned and properly adjusted and secured, as shown in Fig. 5. The cloak is then thrown or placed around the shoulders, with the ends 50 of the drawing-string 9 and the straps 22 brought over the shoulders to the front of the person. The straps 22 are then crossed, carried to the back of the person, and tightly buckled. The cloak is then buttoned at the 55 front and the vizored hood pulled over the head. As thus appareled the person will be

completely enveloped from head to foot in a neat and attractive-appearing storm-suit—one which will permit of the free use of the hands to manipulate a bicycle and which can 60 be worn without the least discomfort after the storm has ceased.

In Fig. 7 the suit is shown cut from two pieces *g* and *h*, which when properly stitched together will produce the cap, cloak, and leggings complete, with the leggings permanently attached to the cloak. In cases where it is desired to have a wider cloak side pieces *i i* are stitched to the outer side edges of the pieces *g* and *h*. When, however, the suit is 70 cut from two pieces, the leggings are made to button or lace or be strapped together on the inside of the leg.

It will be evident that by arranging the leggings as heretofore described, and shown 75 in Fig. 1, the suit can be rolled into a very small bundle or package and conveniently carried by a rider or other person when long trips are taken, and it will also be evident that slight changes may be made in the general form and arrangement of the various parts of my improved suit without departing from the spirit and scope of my invention or sacrificing the principle thereof, and therefore I do not wish to be understood as limiting myself to the exact construction herein set forth.

Having thus fully described my invention, what I claim, and desire to secure by Letters Patent, is—

1. The combination with a cloak or cape having depending securing-straps and a drawing-string, and a hooded cap attached to the cloak or cape; of a pair of leggings and means for supporting them from the lower portion 95 of said cape, substantially as specified.

2. The combination with a cloak or cape having depending securing-straps and a drawing-string, a hooded cap attached to the cloak or cape, and arm-straps to the inside of said 100 cape; of a pair of leggings and means for supporting them from the lower portion of said cape, and means, substantially as described, located at the upper portion of the cape, for securing said leggings within the cape when 105 not in use.

In testimony whereof I affix my signature in the presence of two witnesses.

PHILIP KAUFMAN.
